UNITED STATES PATENT OFFICE.

WILLIAM R. FOX, OF GRAND RAPIDS, MICHIGAN.

AUXILIARY STOP FOR TYPE-WRITER CARRIAGES.

No. 856,629.

Specification of Letters Patent.

Patented June 11, 1907.

Application filed September 16, 1904. Serial No. 224,763.

To all whom it may concern:

Be it known that I, WILLIAM R. FOX, a citizen of the United States, residing at the city of Grand Rapids, county of Kent, State of Michigan, have invented certain new and useful Improvements in Auxiliary Stops for Type-Writer Carriages, of which the following is a specification.

This invention relates to improvements in auxiliary stops for typewriter carriages, although, of course, the stop can be made use of as a main stop if desired.

The stop is specially adapted for use with tabulator devices for typewriters, like those described in my patent application Serial No. 206,684, filed May 6th, 1904.

The objects of this invention are: First: To provide an effective adjustable stop which can be readily removed and put in place, but which is very securely held in place when in position on the carriage of the typewriter. Second: To provide an improved spring means for retaining the stops in position. Third: To provide an improved construction of stop which is very compact in use.

Further objects will definitely appear from the detailed description to follow.

The objects of this invention are accomplished by the devices and means described in the following specification.

The invention is clearly defined and pointed out in the claims.

A structure embodying the features of my invention is clearly illustrated in the accompanying drawing forming a part of this specification, in which—

Figure 1 is a detail rear elevation view of a typewriting machine with two of my improved stops in position, only portions of the frame work of the machine being illustrated. Fig. 2 is a detail plan view of the rear bar of the carriage with the stops in position. Fig. 3 is an enlarged detail inverted view of one of my improved stops, with portions of the rear bar C of the carriage. Fig. 4 is a transverse sectional view taken on line 4—4 of Fig. 3, showing other details of construction. Fig. 5 is a side elevation view of one of the stops removed from the bar.

In the drawing, the sectional views are taken looking in the direction of the little arrows at the ends of the section lines and similar letters of reference refer to similar parts throughout the several views.

Referring to the drawing, in Fig. 1 the main parts of a typewriting machine are shown, being the main frame work A with its top plate A' on which the carriage B is mounted. Arms B' extend rearwardly from the said carriage and support what I have denominated the rear bar of the carriage. This bar is provided with teeth like the teeth on a rack, the teeth being preferably perfectly square. This bar is provided with the regular adjustable stops G at each end, and the usual swinging stop bar E is provided for engagement with the same. My improved auxiliary stops D D are placed on this back rack bar C, as clearly appears in Fig. 2. In the preferred form, these auxiliary stops consist of a piece of sheet metal folded upon itself, with a transverse notch f cut up in the center, as clearly appears in Fig. 5, the sides of the plate being separated sufficiently to enter the notches between the teeth on the bar C, thus providing a wide base for the stop. The lower edges or lips of the notch are rounded at f' so that they can be readily crowded onto the back bar. A spring d, with a curved engaging portion d', is placed within the stop and is held in position by the handle D' above, which has a stud extending down through the spring which is riveted thereto. When the stop is crowded in place, the spring presses against the bar C and forces the opposite side into close engagement with the teeth of the bar C, and the projection d' hooks under the bar and retains the stop so effectively in position that considerable force is required to remove it, thus making the stop very secure when it is in place.

One of the sides of the plate is cut away at D'' so that but a single projection is presented as a stop. This is desirable where the sides of the plate are close together, as it permits the free movement of the vertically adjustable tabulator bars described in my former application for patent above referred to.

When my improved stop is used, it will be observed that many stops can be very readily placed on the back bar C and that they will be very effective in use.

By the particular formation of the spring, the stops are retained as securely in place for all practical purposes as though they had been screwed or riveted in position, and, at the same time, they are readily removable and adjustable along the bar.

I have illustrated my invention in its most

approved form. The form of the same could be varied, so far as general features are concerned so long as the equivalent parts are provided with the spring d and its engaging projection d' . Certain of the claims are, of course, to the specific approved form which I have shown.

Having thus described my invention, what I claim as new and desire to secure by Letters Patent is—

1. A stop D for a typewriter, adapted for use on the back bar C of the carriage, consisting of a sheet of metal folded upon itself, with a transverse notch f therethrough having the lips beveled at f' , to readily pass onto the notched back bar C of the carriage, one of the lips being cut away at D'' ; a spring d to embrace the back bar and with a projection d' arranged to engage beneath the back bar C; and a handle D' with a stud riveted through the spring to hold it in position, co-acting for the purpose specified.
2. A stop D for a typewriter, adapted for use on the back bar C of the carriage, consisting of a sheet of metal folded upon itself, with a transverse notch f therethrough having the lips to readily pass onto the notched back bar C of the carriage, one of the lips being cut away at D'' ; a spring d to embrace the back bar and with a projection d' arranged to engage beneath the back bar C; and a handle D' with a stud riveted through the spring to hold it in position, co-acting for the purpose specified.
3. A stop D for a typewriter, adapted for use on the back bar C of the carriage, consisting of a sheet of metal folded upon itself, with a transverse notch f therethrough, having the lips to readily pass onto the notched back bar C of the carriage; a spring d to embrace the back bar and with a projection d' arranged to engage beneath the back bar C; and a handle D' with a stud riveted through the spring to hold it in position, co-acting for the purpose specified.
4. A stop D for a typewriter, adapted for use on the back bar C of the carriage, consisting of a sheet of metal folded upon itself, with a transverse notch f therethrough, having the lips to readily pass onto the notched back bar C of the carriage; and a spring d to

embrace the back bar and with a projection d' arranged to engage beneath the back bar C, co-acting for the purpose specified.

5. A stop D for a typewriter, adapted for use on the back bar C of the carriage, consisting of a suitable body to embrace the back bar; a spring d to embrace the back bar and with a projection d' arranged to engage beneath the back bar C; and a handle D' with a stud riveted through the spring to hold it in position, co-acting for the purpose specified.

6. A stop D for a typewriter, adapted for use on the back bar C of the carriage, consisting of a suitable body to embrace the back bar; and a spring d to embrace the back bar and with a projection d' arranged to engage beneath the back bar C, co-acting for the purpose specified.

7. A stop for a tabulator adapted for use on the back-bar of the carriage of a type-writing machine, consisting of a piece of metal folded upon itself and with a transverse slot f therethrough so that the edges of the sheet metal will engage between the teeth on the rack; a handle terminating in a rivet; a spring with an engaging projection arranged within the said stop and held in position by the rivet of the handle, for the purpose specified.

8. A detachable sheet metal stop folded to form two substantially parallel slot engaging securing arms, each of said arms being bifurcated to straddle a supporting rod.

9. A detachable sheet metal stop folded to form two substantially parallel slot engaging securing arms, each of said arms being bifurcated to straddle a supporting rod, and securing means carried by said stop.

10. A detachable sheet metal stop folded to form two substantially parallel slot engaging securing arms, each of said arms being bifurcated to straddle a supporting rod, and a clamping spring carried by said stop.

In witness whereof, I have hereunto set my hand and seal in the presence of two witnesses.

WILLIAM R. FOX. [L. s.]
